PRINTING MECHANISM

Otis F. Wood, New Brighton, N. Y.

Application March 3, 1931, Serial No. 519,710

9 Claims. (Cl. 101—122)

My invention relates to the printing art and has for an object to provide a new printing mechanism.

The invention is particularly adapted for the printing of textile fabrics although it is also applicable for the printing of paper or other sheet material.

Fabric printing machines as heretofore constructed have been of the intaglio type, i. e. the design is etched or engraved in a printing cylinder and ink applied to the cylinder is wiped off except for that which is caught and retained in the etched depressions. When the cylinder is pressed against the fabric the latter picks up the ink out of the depressions. Usually, the printing cylinder is of copper and it must be ground and finished to a very smooth and true surface with no flaws or scratches to catch the ink and produce false lines and areas in the printed design. The cost of these cylinders and of preparing them for printing is high, particularly in cases where a large design is to be printed, because the circumference of the cylinder must be equal to the length of the design.

It is an object of my invention to dispense with the etched copper cylinders and replace them with printing elements of extremely low cost. Instead of an etched cylinder, I use an endless flexible band with openings therein forming the design. The band is then pressed against the web that is to be printed and a roller forces ink, dye or other printing fluid through the openings in the band and upon the web.

My invention is thus a development of and improvement on what is known in the art as "screen printing". Heretofore this type of printing has had to be done by hand. The printing element consists of a strip of silk bolting cloth which is prepared for printing by masking out the parts that are not to be printed with shellac, lacquer or the like. The strip is then laid on and clamped to the fabric that is to be printed and liquid coloring matter is deposited on the strip. After which the operator uses a squeegee to force the coloring matter through the unmasked parts of the strip to print the fabric. This process must be repeated for consecutive sections of the fabric, care being taken to match up the designs at the junctions of such sections. My invention calls for the use of endless bands in place of the short strips so that the pattern is repeated throughout the length of the web that is being printed, without showing any joints and without requiring any skilled matching at the junctions of the repeats. My invention also includes automatic

means for feeding the printing band with the web, and for forcing ink or other printing fluid through the band.

While my invention contemplates the use of endless bands of bolting cloth or other textile fabric for the printing element, I prefer in many instances to use a metallic printing band so as to prevent stretching. This is of prime importance in multi-color printing where each impression must register perfectly with the rest of the printings.

Another object is to provide for interchanging the printing elements as desired, and to this end I provide a mounting for the printing band of such character that the band may readily be removed from the mounting and be replaced with another printing element.

Another object of the invention is to provide under normal conditions a surface bearing, rather than a line bearing, of the printing band against the impression cylinder, so as to confine the printing fluid to the design and prevent spread of the fluid under the band at the margins of the design, as would occur if the band were tangent to the web.

However, my invention has for a further object to provide a mounting for the band and its inking system such that the band may be adjusted toward or from the impression cylinder to vary the depth or heaviness of the impression made on the web. Thus the band may be withdrawn to such an extent as to provide substantially a line contact with the web. In such case, undue spread of the printing fluid may be prevented by using a fluid of increased viscosity.

Other objects and advantages of the invention will appear in the following description of a preferred embodiment and thereafter the novelty and scope of the invention will be pointed out in the claims.

In the accompanying drawings:

Figure 1 is a fragmental view mainly in section of a two-color printing machine embodying my invention, the section being taken substantially on the line 1—1 of Fig. 3;

Fig. 2 is a side elevation of a portion of the printing machine and looking in the same direction as in Fig. 1;

Fig. 3 is a view in transverse section taken on the line 3—3 of Fig. 1;

Fig. 4 is a detail view showing a section taken on the line 4—4 of Fig. 3;

Fig. 5 is a fragmental view in perspective of a printing belt;

Fig. 6 is a fragmental plan view of a modified form of printing belt; and

Fig. 7 is a view in section taken on the line 7—7 of Fig. 6.

5 The main frame of my machine comprises a pair of uprights 10 which provide bearings for a transverse shaft 11. Mounted upon and secured to this shaft is an impression cylinder 12. The shaft 11 is provided with a pulley 13, at one end which is driven by a belt (not shown) from a pulley 14 over head. An endless blanket 15 of rubber or other suitable material passes about the impression cylinder 12 and is guided to and from said cylinder by rolls 16 and 17. A blotter strip 18 passes around the impression cylinder 12 over the blanket 15, being guided over rolls 19 and a fixed guide 20. The web 21, which is to be printed, passes about the impression cylinder 12 over the strip 18, being led into the machine 20 over a roller 22 and fixed guide 23.

Each frame member 10 is provided at the right hand side, as viewed in Fig. 1, with a slideway 25 in which slides a carriage 26. The carriages provide bearings for a printing cylinder 27 which 25 is adapted to bear against the web 21. This cylinder is etched or engraved with the design that is to be printed on the web and is inked in the usual well known manner. However, the inking mechanism is not shown in the drawings. The 30 mechanism so far described follows the standard practice in machines of this character.

The frame members 10 are provided with arms 30 and 31 respectively, which project toward the left, as viewed in Figs. 1 and 2. The arm 30 is provided with ways 32 for a slide block 33. Hinged upon the slide block at 34 is a carriage 35 in which is supported my improved printing band. This carriage comprises a U-shaped frame 36 which at its free end is formed with a lug 37 adapted, when the parts are in printing position, to engage a hook 38 formed on the arm 31.

The frame 36 provides bearings for two shafts 40 and 41 at its forward end and a shaft 42 at the rear end. Mounted on and fixed to these 45 shafts are rolls 43, 44 and 45 respectively. Sleeved upon these rolls is an endless printing band 47. The shaft 42 is adjustable in slots 36a formed in the frame 36, so as to vary the tension of the band 47. Each end of the shaft engages a screw eye 39 which has sliding engagement with a lug 36b formed on the frame 36. Nuts 39a on the screw eyes and bearing against opposite sides of the lugs serve to hold the shaft 42, at any desired 50 adjustment. The latter is formed with openings therein through which the design is printed upon the web 21. Also carried by the frame 35 is a pan 48 for printing fluid. The fluid used depends upon the nature of the material to be printed. In the case of fabrics, it is more in 55 the nature of a dye, whereas if paper is being printed it may be more like printers' ink although not so heavy and viscous. For convenience, the fluid will hereinafter be termed "ink" although the term will be understood to apply to any printing fluid. In the pan 48 is mounted a fountain roll 49. An inking roll 50 picks up ink from the fountain roll 49 and presses it through the openings in the printing band and upon the web 21. A doctor blade 51 serves to limit the thickness 60 of the fluid film picked up by the roll 50. The ink pan 48 is removably mounted in the frame 36 and may be withdrawn therefrom when desired.

Since the carriage 35 is hinged to the slide 75 block 33 it may be moved toward and from the im-

pression cylinder or platen 12. The purpose of this is to permit of replacing the printing band with another band. When this is to be done the carriage is withdrawn to the position shown in Fig. 2; the ink pan is detached from the frame 36 5 and removed; the screw eyes 39 are adjusted to slacken the tension in the printing band; the carriage is swung up on its hinge 34 to clear the arm 31; and the band 47 is slipped off the rolls 43, 44 and 45, in axial direction. Another band 10 may now be sleeved upon said rolls and after which carriage is dropped to normal horizontal position with the lug 37 resting on the arm 31, and the nuts 39a are adjusted to give the band 15 the desired tension. If a different color of ink 15 is to be used the inking rolls are also replaced and a fresh ink pan is secured to the carriage. The carriage then is moved forward to printing position with the band 47 bearing against the web 21. The ease with which the printing bands 20 may be replaced is an important feature of my invention.

Slidable in the ways 32 with the slide block 33 is another block 53. The latter provides a bearing for an adjusting screw 54 which is 25 threaded into a lug 55 carried by the slide block 33. A threaded shank 56 depends from the block 53, passing through a slot 57 formed in the arm 30. Screwed upon this shank and bearing against the underface of the arm 30 is a clamping nut 58. When the carriage 35 is moved toward or from the impression cylinder 12, the block 53 will slide therewith because of its connection by screw 54 to the block 33. When the carriage has been moved forward to approximately the desired position, the nut 58 is turned to clamp the block 53 in fixed position on the arm 30 and thereafter the screw 54 is turned to adjust the pressure of the band 47 against the web 21. The object of varying the pressure 40 is explained hereinafter.

Secured upon the shaft 11 is a gear wheel 60 and mounted on the shaft 40 is a pinion 61. When the carriage 35 is moved to the printing position, the pinion 61 is moved into mesh with the gear 60 and the band 47 is then positively driven through gear 60 and pinion 61. Also on the shaft 62 of the inking roller 50 there is a pinion 63 which meshes with the gear 60 when the carriage 35 is moved to printing position, so that there is also a positive drive of the inking roll 50.

Fig. 2 shows the carriage 35 withdrawn from the impression cylinder 12 and it will be noted that the lug 36 has been withdrawn from under 55 the hook 38 so that the carriage may be swung up on its hinges. However, when the carriage is moved forward to its printing position, the lug 37 is caught under the hook 38 so that there is no danger of lifting or displacement of the carriage during the printing operation.

The printing band 47 may be made in a number of different ways. One form is shown in Fig. 5. This consists of an ordinary wire mesh fabric 65 formed into an endless band by soldering, welding or otherwise securing the ends together. On this band the design is formed by masking or blanking out the background with a suitable filler 66, such, for instance, as celluloid dissolved in acetone. However, any other liquid or plastic filler material can be employed for the purpose which will harden when in place, and which when hardened will be sufficiently flexible to pass around the rolls 44 and bear against the web or fabric 21 without breaking or cracking 75

I may also use a metal filler such as lead, zinc, etc. The filler whether of metal or other material may be etched out to form the design.

As shown in Fig. 5, the open or unfilled part 5 of the wire mesh constitutes the design 67 which is to be printed by forcing ink therethrough. The wires of the fabric run across the design serving to preserve the open spaces against distortion and also to give strength to the printing band. 10 As shown in the drawings, the design includes an annular opening 68 surrounding an "island" 69. The latter is supported and maintained in position by the wires of the fabric. It will be noted that the surface of the band 47 is smooth 15 and the margins of the design are clear cut. When the ink is pressed through the open design by the roll 50, it might at first be thought that the net work of wires in the fabric would show in the printed design. However, the wire fabric 20 touches the web only at the "knuckle" points where the wires intersect. In other words, there are no line contacts but merely point contacts and the ink used is sufficiently fluid to spread under these knuckles or intersecting points of 25 the wire mesh.

The size of mesh, viscosity of the ink and pressure applied by the inking roll, are all important factors in determining the character of the printing. However, the sharpness of outline is not 30 affected by the coarseness of the mesh, because the margin of the design is not checkered, as it would be were it obliged to follow the pattern of the wire mesh, but may cut across the mesh in any direction desired.

35 As clearly shown in Fig. 1, the band 47 has a broad bearing surface against the web 21. Instead of being merely pressed against the web by the inking roll 50, it is held thereagainst by the rolls 43 and 44 and the web between said rolls is concaved so as to conform to the curvature given to web 21 by the cylinder 12. If the band 47 ran tangent to the web 21 instead of having a broad surface contact therewith, or if it were given a convex form about the inking roll 45 50 so that there was merely a line contact between the band 47 and the web 21 there would be a chance for the ink to ooze out of the openings in the band 47 at each side of the line of contact with the web 21, thus distorting and blurring the design. However, when a light impression is desired the pressure of the printing band is reduced by adjusting the screw 54. As the 55 pressure is reduced the area of engagement of the band with the web approaches a line contact and ink of greater viscosity must be employed to prevent it from oozing out beyond the boundaries of the design. As the pressure of the band is reduced the slack is taken up by adjusting the roll 45. If the carriage is to be adjusted 60 away from the impression cylinder the printing roll must be capable of corresponding adjustment toward the cylinder. Such adjustment is provided in the bearings of the shaft 62, set screw 62a serving to retain the shaft at the desired 65 adjustment. The pan 48 and roll 49 are also correspondingly adjustable.

Instead of using a wire mesh for the band 47, I may employ a netting of other material, or, I may employ a band of sheet metal with perforations formed therein. It is preferable to form the perforations only in the design leaving the rest of the band imperforate and avoiding the use of fillers. The following method of forming the band constitutes a part of my invention. The 75 thin sheet of metal 70 is first embossed with in-

tersecting ribs 71 on one face thereof, the other face being left smooth. The intersecting ribs produce a grid-like formation, such as shown in Fig. 6, with rectangular pockets or depressions 72. The design may then be photographed or otherwise formed on the flat face of the metal sheet, after which the design is etched out until it eats through the bottom walls of the pockets 72, leaving open spaces sharply defined on the smooth face of the sheet by marginal walls 73. 10 The sheet is then formed into an endless band by soldering, brazing or welding or locking the ends together. The band is used in the press with the 15 smooth side bearing against the web 21, so that the ink will pass under the net work of bars 71, and the latter will not contact with the web. It will be understood that in Fig. 7 the thickness of the band is exaggerated, for the purpose of 20 clarity.

As so far described, I have referred to the printing band as a screen through which ink is forced to print the web. However, it is within the purview of my invention to use the imperforate areas of the band as printing surfaces. To this end, I provide on the carriage 35 a pair of brackets 75 which carry an inking roll 76 adapted to bear on the band where it passes about the roll 45. The roll 76 is supplied with ink by a fountain roll 77 running in an ink reservoir 78. Thus, the web may be printed in one color with ink applied to the surface of the band and with ink of another color forced through the 30 openings in the band.

While in Fig. 1, I have shown only one printing band unit, obviously a number of printing band units could be applied to the same machine to produce multi-color printing. The printing band may be used in connection with one or more 40 etched copper cylinders, as shown in the drawings, or the latter may be replaced with a printing band unit, if so desired.

While I have described a preferred embodiment of my invention, it will be understood that 45 this is to be taken as illustrative and not limitative and that I reserve the right to make such changes in methods and in form, construction and arrangements of parts, as fall within the spirit and scope of the following claims.

I claim:

1. A web printing press comprising a printing cylinder, a carriage movable toward and from the cylinder, a set of rolls supported by the carriage, an endless printing band carried by the rolls, said band having openings therein forming a design, a pair of the rolls being adapted to bear against the cylinder whereby the run of the band between said rolls will be concaved when the carriage is advanced to printing position, means for 55 guiding a web between the band and the cylinder, and means carried by the carriage for forcing ink through the openings in the band within the concaved area thereof to print the design 60 on the web.

2. A web printing press comprising a printing cylinder, a carriage movable toward and from the cylinder, a set of rolls supported by the carriage, an endless printing band sleeved on the rolls, said band having openings therein forming a design, a pair of the rolls being adapted to bear against the cylinder whereby the run of the band between said rolls will be concaved when the carriage is advanced to printing position, means for 70 guiding a web between the band and the cylinder, 75

der, means carried by the carriage for forcing ink through the openings in the band within the concaved area thereof to print the design on the web, and means for adjusting the pressure of 5 the band against the web.

3. A web printing press comprising a printing cylinder, a carriage movable toward and from the cylinder, a set of rolls supported by the carriage, an endless printing band sleeved on the 10 rolls, said band having openings therein forming a design, means for adjusting one of the rolls to vary the tension of the band, a pair of the rolls being adapted to bear against the cylinder whereby the run of the band between said rolls 15 will be concaved when the carriage is advanced to printing position, means for guiding a web between the band and the cylinder, means carried by the carriage for forcing ink through the openings in the band within the concaved area there- 20 of to print the design on the web, and means for adjusting the pressure of the band against the web.

4. A web printing press comprising a printing cylinder, a carriage movable toward and from the cylinder, a set of rolls supported by the carriage, an endless printing band carried by the 25 rolls, said band having openings therein forming a design, a pair of the rolls being adapted to bear against the cylinder whereby the run of the 30 band between said rolls will be concaved when the carriage is advanced to printing position, means for guiding a web between the band and the cylinder, means carried by the carriage for forcing ink through the openings in the band 35 within the concaved area thereof to print the design on the web, and means for adjusting the carriage with respect to the cylinder.

5. A web printing press comprising a frame, an impression cylinder journaled therein, a 40 member movable on the frame toward and from the cylinder, a carriage hinged to the member, rolls supported by the carriage, an endless printing band sleeved on the rolls, the carriage being adapted to be swung clear of the frame to permit of removing the band, means for advancing 45 the carriage toward the cylinder, means for leading a web between the band and the cylinder, and means for inking the band to print the web.

6. A web printing press comprising a printing 50 cylinder, a carriage movable toward and from the cylinder, a set of rolls supported by the carriage, an endless printing band carried by the rolls, said band having openings therein forming

a design, a pair of the rolls being adapted to bear against the cylinder whereby the run of the band between said rolls will be concaved when the carriage is advanced to printing position, means for guiding the web between the band 5 and the cylinder, means for inking the outer face of the band to print the web, and means for forcing ink through the openings in the band within the concaved area thereof to print the de- 10 sign on the web.

7. A web printing press comprising a printing cylinder, a carriage movable toward and from the cylinder, a set of rolls supported by the carriage, an endless printing band carried by the rolls, said band having openings therein forming a 15 design, a pair of the rolls being adapted to bear against the cylinder whereby the run of the band between said rolls will be concaved when the carriage is advanced to printing position, means for guiding a web between the band and the cylinder, 20 means supported by the carriage for inking the outer face of the band to print the web, and means supported by the carriage for forcing ink through the openings in the band within the concaved area thereof to print the design on the 25 web.

8. A web printing press comprising a frame, an impression cylinder journaled therein, a carriage mounted on the frame, rolls supported on the carriage, an endless printing band sleeved on the rolls, means for leading a web between the band and cylinder, means for adjusting the carriage in a plane radial to the cylinder to a printing position with respect to the cylinder or in the opposite direction to a clearance position to 30 permit of removing the band from the rolls, and means for inking the band to print the web.

9. A web printing press comprising a frame, an impression cylinder journaled therein, a carriage mounted on the frame, rolls supported on 40 the carriage, an endless printing band sleeved on the rolls said band having openings therein forming a design, means for leading a web between the band and cylinder, means for adjusting the carriage toward and from printing position 45 with respect to the cylinder said carriage being movable to a clearance position to permit of removing the band from the rolls, means for applying ink to the exterior surface of the band to print the web, and means for forcing ink through the openings in the band within the area of contact of the band with the web.

OTIS F. WOOD.
